UNITED STATES PATENT OFFICE

138,913

DESIGN FOR A BUTTON OR THE LIKE

Sherman H. Dalrymple, Akron, Ohio

Application April 19, 1944, Serial No. 113,305

Term of patent 14 years

(Cl. D29—2)

To all whom it may concern:

Be it known that I, Sherman H. Dalrymple, a citizen of the United States, residing at Akron, in the county of Summit and State of Ohio, have invented a new, original, and ornamental Design for a Button or the like, of which the following is a specification, reference being had to the accompanying drawing, forming a part thereof.

In the drawing,

Fig. 1 is a front elevational view of a button, showing my new design; and Fig. 2 is a top plan view thereof, showing in broken lines a threaded post adapted to be passed through a buttonhole of a garment and secured by a nut.

I claim:

The ornamental design for a button or the like, substantially as shown.

SHERMAN H. DALRYMPLE.
